ATTORNEY

UNITED STATES PATENT OFFICE.

JOHN REID PILE, OF OWENSBORO, KENTUCKY.

NAPKIN-HOLDER.

1,253,277.

Specification of Letters Patent. Patented Jan. 15, 1918.

Application filed July 26, 1917. Serial No. 182,966.

To all whom it may concern:

Be it known that I, JOHN REID PILE, a citizen of the United States, residing at Owensboro, in the county of Daviess and 5 State of Kentucky, have invented certain new and useful Improvements in Napkin-Holders, of which the following is a specification.

This invention relates to napkin holders 10 and the primary object of the invention is to provide a device that may be attached around the neck of the user and secured to a napkin whereby the garments of the person using the device may be protected.

Another object of the invention is to provide a napkin holder of this character that will obviate the necessity of attaching the napkin to the collar or front of the garment of the wearer in the manner now generally 15 employed.

A further object of the invention is the provision of a napkin holder constructed to support one of the marginal edges of the napkin so that it will be stretched to permit 20 a broad expanse of napkin to cover the front of the garment of the user.

The above and additional objects are accomplished by such means as are illustrated in the preferred embodiment and in the accompanying drawings, wherein like characters denote like or corresponding parts throughout the several views, in which:

Figure 1 is a perspective view of the device constructed in accordance with my invention, showing a napkin attached thereto, the napkin being illustrated by dotted lines.

Fig. 2 is a detail cross section on the line 2-2 of Fig. 1.

Fig. 3 is a front elevation of a modified 40 form of the invention.

Fig. 4 is a detail section on the line 4-4 of Fig. 3.

Referring particularly to Figs. 1 and 2 of the drawing, it will be observed that the 45 clamp ring 1 is constructed from a length of wire having its terminals provided with rounded ball-shape guards 2. This clamp ring is preferably constructed from spring wire so that the gap in the ring may be 50 widened to permit the clamp ring to be placed around the neck of the user. The resiliency of the wire will cause the gap to close as soon as it has been applied and the ring will thereby be supported in position 55 about the neck of the wearer.

Diametrically opposite from the guards 2

is a thin metallic plate 3, the lower edge of which is rolled to provide the sleeve 4. At each end of the upper edge of the plate the latter is provided with an extension 5 which 60 is bent around the ring, intermediate the ends thereof, thereby forming the loops 6 for attaching the plate to the ring. The ends of the extensions are again bent to form the hooks 7 disposed directly beneath the 65 loops 6.

A stretcher bar 8 is supported by the plate 3 and is formed of a suitable length of wire bent to provide the upper arm 9, and the lower arm 10. The lower arm 10 is extended 70 through the sleeve 4, while the upper arm 9 is embraced by the hooks 7. In this manner, the stretcher bar is supported from the plate 3. An upwardly turned loop 11 is formed at each end of the stretcher bar by bending the 75 wire which forms the same, and the top portion of each loop is substantially straight to form a clip bar 12, shown in cross section in Fig. 2. A spring clip 13 is fixed to each clip bar 12, and the clip engages the side portions of the loop for permitting a napkin to be clamped between the clip 12 and the loop 11.

Referring to Figs. 3 and 4 of the drawing, it will be noted that the ring 14, which is 85 identical in construction with the ring 1, is attached to a pair of loops 15 formed at the upper marginal edge of a stretcher bar 16, formed of a length of comparatively thin material, preferably metal. Each end of the 90 bar is bent upwardly to provide the clip plate 17 and the upper marginal edge of the clip plate is bent upon itself to form the clip finger 18, the same gaining their resiliency from the bend provided when forming the 95 clip. These clips support the napkin, and it will be noted that the length of the bar permits the greater portion of the marginal edge of the napkin to be held in stretched position and in close proximity to the ring 14. 100

It is to be noted that both of the forms above described are extremely simple in construction and operation and it will be apparent that the devices may be made in various sizes to suit children or adults.

I claim:

1. A napkin holder comprising a substantially circular clamp member adapted to be spread apart for applying it to operative position, and being resilient to assume operative position when applied, and a stretcher bar attached intermediate the ends of the 110

said clamp ring and provided with clips at its ends.

2. A napkin holder comprising a ring having its ends normally in close proximity and adapted to be spread apart for applying the ring to operative position, a straight stretcher bar suspended from the ring intermediate the ends thereof, and having its ends upturned, and clips carried by the upturned ends of the said stretcher bar.

3. A napkin holder comprising a relatively long stretcher bar, having upturned portions at each end, clips formed on the upturned portions, the intermediate portion of the bar being provided with loops, and a ring received in the said loops.

4. A napkin holder comprising a relatively

thin plate, a clamp ring supporting the plate, and a pair of clamps arranged in spaced relation and supported by the plate. 20

5. A napkin holder comprising a plate, loops formed on the plate, a stretcher bar formed of a length of wire received in the said loops, the said stretcher bar having upturned portions at each end, a resilient supporting ring attached to the said plate, the latter being provided with hooks engageable with the said ring. 25

In testimony whereof I affix my signature in presence of two witnesses.

JOHN REID PILE.

Witnesses:

LOUISE McDANIEL,

A. B. MENSER.
